CLAIM

The ornamental design for a display screen or portion thereof with graphical user interface, as shown and described.

DESCRIPTION

The sole FIGURE is a front view of a display screen or portion thereof with graphical user interface showing the claimed design.

The outermost evenly spaced broken lines in the drawings show an electronic device, which is the environment of the design and forms no part of the claimed design. The dot-dash broken lines in the drawings show a display screen or portion thereof and form no part of the claimed design. The remaining broken lines showing portions of the graphical user interface form no part of the claimed design.
